(57) **CLAIM**

We claim the ornamental design for a wall anchor light bar fixture, as shown and described.

DESCRIPTION

FIG. 1 is a top perspective view of a wall anchor light bar fixture showing the new design;

FIG. 2 is a left side view thereof;

FIG. 3 is a right side view thereof;

FIG. 4 is a top view thereof;

FIG. 5 is a bottom view thereof;

FIG. 6 is a back view thereof; and,

FIG. 7 is a front view thereof.

The broken lines represent portions of the wall anchor light bar fixture and form no part of the claimed design.
